CONTAINER FOR FLUID CLEANER FOR CHAMOIS OR THE LIKE

Marrs F. Koontz, Houston, Tex.

Application October 29, 1956, Serial No. 43,559

Term of patent 14 years

(Cl. D49—1)

The figure in the drawing is an isometric view showing my new design for a container for fluid cleaner for chamois or the like, with the vertical bar on the opposite side of the container being the same in appearance as the two shown.

I claim:

The ornamental design for a container for fluid cleaner for chamois or the like, as shown and described.
